UNITED STATES PATENT OFFICE.

WILLIAM C. GARWOOD, OF DAYTON, OHIO, AND CARL P. WEBER, OF WASHINGTON,
DISTRICT OF COLUMBIA.

AIR-COMPRESSION STARTER.

1,405,913.

Specification of Letters Patent. Patented Feb. 7, 1922.

Application filed January 2, 1920. Serial No. 349,104.

To all whom it may concern:

Be it known that we, WILLIAM C. GARWOOD and CARL P. WEBER, citizens of the United States of America, residing at Dayton, in the county of Montgomery, State of Ohio, and at Washington, District of Columbia, respectively, have invented a certain new and useful Improvement in Air-Compression Starters, of which the following is a specification.

Our invention relates to a starting device for internal combustion engines in aircraft.

The object of our invention is chiefly to enable the engineer or pilot of said aircraft to restore action to the engine after it has been accidentally stalled while said aircraft is in flight, i. e., above the ground, thereby preventing the necessity of landing in order to prepare for continuing flight.

Another object of our invention is to provide means whereby the engine may be started without the use of a second or auxiliary engine.

Another object of our invention is to provide means for repeated action on the engine in the event of the spark not taking effect upon the explosive means the first time.

Another object is to provide means for setting the device so that it may be operated instantly after the engine is stalled.

A further object is to provide means whereby the set or release of the device may be read upon the instrument board by the pilot.

Further objects and advantages will appear as the description proceeds.

Referring now to the drawings:—

Fig. 1 represents a side elevation of the starter and associated parts.

Fig. 2 represents a projected view of Fig. 1.

Fig. 3 represents an attachment whereby the action may be withheld until the moment when it should be used.

Figs. 4 and 5 are projections of each other and show a means of indicating the state of operation of the starter (whether it is set for action or released).

Referring now in detail to Fig. 1, 1 represents the propeller shaft of the engine, and 2 a cam which fits loosely as a collar upon the shaft 1. The cam 2 is surmounted by a piston 3 containing ball bearing 3' which operates vertically in a cylinder 4. The cylinder 4 is held in place by a brace 5 also

containing ball bearing 5' where it is supported by the shaft 1. Supports connected to the one shown at 5, which function horizontally, and are fastened to the sides of the ship, are not indicated in the drawing, (all unnecessary structure having been removed to aid in the simplicity of presentation). A large gear wheel 6 is placed upon the shaft 1 on one side of the cam 2, and operates upon the threaded section 7 by means of the corresponding threads 7', while on the opposite side of the cam 2 a cup-shaped collar 8 carries a spring 9 in its recess. Connected now to the large gear wheel 6 is a train of smaller gear wheels 10 carried on shafts 10' which are supported at their ends by the brace 5. A long shaft 11 connected at one end to the last of the smaller gear wheels 10 and also supported by the brace 5 extends to the instrument board of the craft, and terminates in the form of a crank handle 12. Toothed sections 13 and 13', which are placed on opposite sides of the cam 2, operate in conjunction with corresponding teeth in the larger gear wheel 6 on the one side and 80 the cup-shaped collar 8 on the other.

Having described the appearance of Fig. 1, we will proceed with the operation.

Turning the handle 12 which is in convenient reach of the operator (pilot) will rotate the shaft 11 and consequently operate the train of gears indicated by 10 and 10'. These terminating in the larger gear wheel 6, force it to travel on the screw threads 7 and 7' until it reaches the cam 2, whereupon the teeth 13 of the cam 2 mesh with those of the larger gear wheel 6 and thus rotate the said cam in unison. As the cam 2 rotates upon the shaft 1 the eccentric nature of its construction carries the piston 3 upward in a vertical direction. This compresses the air in the cylinder 4 and when the cam 2 has passed the maximum position of compression upon the piston 3, the accumulated energy in the compressed air contained in cylinder 4, forces the cam 2 the rest of the way on the opposite side of its minimum position with a rapid action. Before the cam 2 reaches the position where this said rapid action takes place, the larger gear wheel 6, 105 traveling on the screw threads 7, also forces the said cam 2 upon the shaft 1 toward the collar 8 which is secured to the said shaft 1. When the cam 2 reaches the collar 8, the teeth 13' of the said cam mesh with those of 110

the collar 8 and prepare to carry the shaft 1 in unison with the rest of the moving apparatus. When this point of action has been reached, the cam 2 is then ready for accumulated energy of the compressed air, and the shaft 1 turned rapidly upon its axis produces the desired effect upon the gas engine of the craft necessary for starting. The use of the spring 9 will be described in conjunction 10 with Fig. 3.

Fig. 2 being a projection of Fig. 1 shows the elliptical shape of the cam 2, and as the action has been mentioned in the foregoing figure nothing more needs to be described except to state that the brace 5 has been removed in order to show the cam 2 to better advantage.

In Fig. 3 we have shown as before the propeller shaft 1 and the cam 2 of Figs. 1 and 2, 20 and the collar 8 containing the spring 9 of Fig. 1. In addition, and forming the principal feature of this figure, is a toothed bar 14 which operates upon a toothed wheel segment 14', said toothed wheel segment 14' being fastened to a second cam 15, the nose of which rests upon the cam 2. The toothed bar 14 is fastened to a bell-crank lever 16 which in turn is fastened to a connecting rod 17, the said rod 17 being fastened to a 30 second bell-crank lever 18 having a handle 19 for manual operating purposes.

Now referring to the action:—In the position illustrated the cam 15 is holding the cam 2, which may slide upon the shaft 1, away 35 from the collar 8. Now when it is desired to put the starter into action the handle 19 is turned to the left, the section 18 coming toward the operator. This pulls the connecting rod 17 forward and in turn operates the lever 16. This now draws the toothed bar 14 toward the right, carrying with it the toothed wheel segment 14' which forces the nose of the cam 15 to the left and away from the cam 2. The cam 2 is now free to travel 40 toward the collar 8 as described in Fig. 1.

After the engine of the aircraft has been started, the spring 9 in the recess of the collar 8, which has been previously contracted by contact with the cam 2, expands and throws 50 the cam 2 away from the collar 8, thereby relieving all action upon the shaft and allowing the engine to operate with complete freedom.

In Figs. 4 and 5, which are projections of each other, we have shown again the shaft 1 and the cam 2 of Fig. 1, and in conjunction with these we have also shown a small wheel 20 placed upon a shaft 21 and resting against the cam 2. The shaft 21 is fastened 60 to a bell-crank lever 22 which is in turn fastened to one end of a connecting rod 23, the other end being coupled with a second bell-crank lever 24. At this point a second connecting rod 25 joins the second bell-crank 65 lever 24 with an indicator 26 of a dial 27,

which dial 27 is placed upon the instrument board of the aircraft. One or more notches 2¹ are filed into the working face of the cam 2 for a purpose hereinafter explained. A spring placed upon the fulcrum of the lever 22 holds the wheel 20 in place against the cam 2, but is not shown in the drawing.

The operation of this portion of our invention is as follows:

As the cam 2 in Fig. 4 turns from the 75 position indicated by the solid line to that shown by the dotted line, the wheel 20 recedes, forcing the shaft 21 to turn the lever 22 counter clockwise. This action pulls the connecting rod 23 and carries the second 80 lever 24 in synchronism with that of lever 22, and in turn pulls the second connecting rod 25 to the left. This moves the indicator 26 upon the dial 27 which is upon the instrument board of the craft, as previously stated, 85 and shows that the cam 2 is in action. The letters S and R upon the dial represent indications of the cam, being "set" for action, or in a state of "rest". Referring to the notch 2¹ on the surface of the cam 2; when 90 the said cam is ready for action (set) the lower end of the piston 3 of Fig. 1 having a corresponding tongue, not indicated in the drawing, will settle into the notch 2¹ and hold the cam 2 from slipping back before it 95 is brought into final action.

What is claimed is:

1. The combination with a propeller shaft, of an eccentric normally loose thereon, a compression chamber, a reciprocating actuating piston in said chamber, speed reducing gear for imparting a rotative movement to said eccentric to move the piston to compressing position, and clutch means to automatically connect and disconnect the eccentric with said shaft. 100

2. The combination with a propeller shaft, of an eccentric normally loose thereon, energy storing and delivering means in cooperative relation to said eccentric, speed reducing gear for imparting a rotative movement to said eccentric, and clutch means to automatically connect and disconnect said eccentric with said shaft. 110

3. The combination with a propeller shaft, of an eccentric normally loose thereon, energy storing and delivering means in cooperative relation to said eccentric, speed reducing gear for imparting a rotative movement to said eccentric, and clutch means having a threaded connection with said shaft to automatically connect and disconnect said eccentric with said shaft. 115

4. The combination with a propeller shaft, of an eccentric normally loose thereon, energy storing and delivering means in cooperative relation to said eccentric, speed reducing gear for imparting a rotative movement to said eccentric, and clutch means to automatically connect and disconnect said eccentric 120

125

130

with said shaft, a distantly located indicator, and connecting means between said eccentric and indicator to visualize the position assumed by the eccentric.

5 5. The combination with a propeller shaft, of an eccentric normally loose thereon, energy storing and delivering means in cooperative relation to said eccentric, speed reducing gear for imparting a rotative movement to
10 said eccentric, and clutch means to automat-

ically connect and disconnect said eccentric with said shaft, a distantly located indicator, and connecting means actuated by the eccentric and controlling the action of said indicator.

15 In testimony whereof, we affix our signatures.

WILLIAM C. GARWOOD.
CARL P. WEBER.
